Primary Examiner — Charles D Hanson(74) *Attorney, Agent, or Firm* — Fitch, Even, Tabin & Flannery LLP(57) **CLAIM**

The ornamental design for dual receptacle carrier, as shown and described.

DESCRIPTION

FIG. 1 is a front perspective view of a dual receptacle carrier showing our new design;

FIG. 2 is a top plan view thereof;

FIG. 3 is a front elevation view thereof;

FIG. 4 is a right side elevation view thereof;

FIG. 5 is a rear elevation view thereof;

FIG. 6 is a left side elevation view thereof; and,

FIG. 7 is a bottom plan view thereof.

The broken lines depict unclaimed portions of the dual receptacle carrier and form no part of the claimed design. The dash-dot broken lines in FIGS. 1, 3, 4, 5, and 6 represent an unclaimed boundary that forms no part of the claimed design.
